UNITED STATES PATENT OFFICE.

GEORGE WRIGHT, OF OAKLAND, CALIFORNIA.

BOAT-LAUNCHING MECHANISM.

Application filed March 12, 1923. Serial No. 624,372.

To all whom it may concern:

Be it known that I, GEORGE WRIGHT, a citizen of the United States, and a resident of Oakland, in the county of Alameda and State of California, have invented new and useful Improvements in Boat-Launching Mechanism, of which the following is a specification.

This invention appertains to certain improvements in apparatus for launching life boats and the like from on board steamships and other types of vessels at sea.

The principal object of the invention is to provide for an apparatus of the class mentioned, and one particularly designed to facilitate and otherwise assure of the positive and quick launching of life boats and the like from wrecked or seriously damaged steamships and other large vessels, and regardless of the degree of listing or rolling of the steamship or vessel from one end or side to the other ends or sides thereof.

Another object of the invention is to provide for an apparatus of the character set forth, and one capable of being readily and inexpensively installed on old vessels, as well as on new vessels under construction, and which is extremely simple in construction and arrangement, and otherwise highly efficient in operation, for the intended purposes thereof.

With the foregoing and other equally important objects in view, the invention resides in the certain novel and useful construction and arrangement as will be herein-after more fully described, set forth in the appended claims, and illustrated in the accompanying drawing, in which:—

Figure 1 is an enlarged fragmentary vertical section taken on the line 1—1 of Figure 2, and shows, in full lines, the normally inoperative position of the launching apparatus with a life boat supported thereon, and, in broken lines, the operative position of the apparatus with the life boat swung to a partial outboard position and ready for the final launching operation.

Figure 2 is a fragmentary top plan view of a portion of the deck of a vessel, and showing a preferred embodiment of the invention as applied thereto,

Figure 3 is an enlarged fragmentary and vertical section taken on the line 3—3 of Figure 1,

Figure 4 is a similar section taken on the line 4—4 of Figure 1,

Figure 5 is another similar section taken on the line 5—5 of Figure 3, and,

Figure 6 is a detail, inside elevation of a modified form of dog or pawl for pivotal attachment to the brase arm.

Referring to the drawing, wherein similar characters of reference designate corresponding parts throughout the several views, thereof, the numeral 10 indicates a portion of the deck or other boat supporting surface of a vessel at one side thereof, which is provided with spaced parallel channels or slotted openings 11 therein, the same being of a suitable length, one corresponding to the other, and opening outwardly through the side edge of the deck or supporting surface 10.

Secured within each of the channels or slots 11, and coextensive therewith, is a bar 12 having a channel way 13 opening through its upper side from points immediately adjacent the ends thereof. Formed medially of the bottom wall of the channel-way 13 is an elongated series of rack teeth 14 having their inclined faces directed toward the outer side edge of the deck 10. Interned from the opposite longitudinal edges of the channel-way 13 are flanges 15 having their opposed edges spaced apart to a slightly greater width than that of the row of rack teeth 14 whereby the latter are exposed through the opening formed therebetween. These flanges 15 extend from the extreme forward and outer ends of the channel-way 13 and terminate at a point slightly short of the rear or inner ends of the same, substantially as shown in Figures 1 and 2, whereby to provide open spaces 16 for the full width of the channel ways.

Pivoted, as at 17, to the extreme forward or outer ends of each of the bars 12 is the outer end of a skid member in the form of a flat bar 18, which is normally disposed to be swung downwardly on its pivot to be supported on the flanges 15. Each of the skid members 18 are preferably made from lengths of wooden timber, and, in which case, is recessed at the under side thereof, at points substantially intermediate the ends of the same to have secured therein a plate 19 to which is pivoted, as at 20 and at its forward end, an arm 21 which is of a width

to pass inwardly of the slotted opening of the channel way 13 and between the opposed edges of the flanges 15. This arm 21 is extended in a rearward direction from its 5 pivot 20 and terminates at a point beyond the inner end of the skid member 18, where it is provided with an angularly disposed elongated portion 22 having an axial bore 23 therein through which is passed a dog or 10 pawl 24 disposed in engagement with the rack teeth 14. This dog or pawl 24 has a reduced outer shank portion 25 having a shoulder 26 formed at its inner connected end and an enlarged finger gripping portion 15 27 at its outer end. The upper or outer end portion of the bore 23 is enlarged to house 20 therein a coiled spring 28 engaged over the shank 25, the inner end of the spring 28 being arranged to bear against the inner shouldered portion 26, of the shank 25 to normally hold the dog or pawl 24 in depressed position, while the outer end of the spring bears against a screw plug 29 closing the open end of the enlarged portion of the 25 axial bore 23, and through which the outer end portion of the shank 25 passes.

Mounted on the inner end of each of the skid members 18 is an angular bracket or plate 30, preferably having its upper part set inwardly of a recess formed in the skid end to lie flush with the upper face thereof, and having spaced rearwardly extended ears 31 through which is engaged a pivot member 32. Engaged on this pivot member 32 30 is the lower end of the lower section 33 of a turn-buckle 34, which, in turn, is operably connected to the upper end of the section 33 by means of a swivel head 35 formed on the latter. Threaded into the upper end 40 of the turn-buckle 34 is an upper rod section 35 which has its free end formed to provide a hooked portion 36 adapted to normally be engaged over the adjacent edge of a life boat or the like A supported cross-wise of the skid members 18, substantially as shown in Figures 1 and 2. By adjusting the turn-buckle 34 to proper length, and with the hooked end portion 36 of the upper rod section thereof engaged over the 45 edge of the lift boat A, the latter will be maintained in balanced position on its keel a.

In the operation of the apparatus thus provided, the life boat A is to be suspended from the usual falls B for purposes of hoisting and lowering the same to and from water-borne position, and when moved in-board of the side of the vessel, is brought to rest cross-wise of the skid members 18 and in parallel relation to the edge of the deck 50 or supporting surface 10. Now, when it is desired to launch the life boat A, and especially if the vessel has been wrecked or damaged so as to list to one side or the other, the turn-buckles 34 will be loosened sufficiently to admit of the hooked ends 36 be-

ing disengaged from the adjacent edge of the life boat A, which will now be sustained in position on the skid members 18 by reason of slack being taken up in the falls B. As the falls B are being manipulated to 70 slightly raise the life boat prior to the swinging of the same to outboard position for lowering, the turn-buckle devices will now be grasped and pulled in an upward direction, whereby the skid members 18 will 75 be swung upwardly on their pivots 17 to outwardly declined positions, substantially as shown in broken lines in Figure 1, when the life boat A will be free to slide downwardly thereof to full outboard position, 80 when the falls B are slackened off for the purpose. As the skid members 18 are swung upwardly on their pivots 17, the arms 21, by reason of their pivotal connections 20 to the under sides of the skid members, will 85 move in a forwardly or outwardly direction therewith, and, upwardly inclined position to act as braces or supporting struts for sustaining the skid members 18 in any desired raised position, such function being permitted to the arms 21 by reason of the dogs or pawls 24 riding freely over the rack teeth 14, in the forward movements of the arms 21, and engaging in front of one of the rack teeth, when the forward movement of the 90 arms ceases.

The inner free end of the arm 21 is maintained in its engaged relation with the channel 13 of each of the bars 12 at all times by means lateral offset portions 21' formed at the extreme inner of free end of the arm 21 and which have sliding engagement with the channel 13 beneath the flanges 15 of the bars 12. These offset portions 21' are preferably 100 of a cylindrical formation, and are inserted into position beneath the flanges 15 through the spaces 16 at the rear ends of the latter, when the parts of the apparatus are assembled and installed. The opposed edges of the flanges 15, together with the offset portions 21', therefore, act to maintain the alignment of the arm 21 with the channel way and the dog or pawl 24 in operative engagement with the rack teeth 14 of each of the bars 12. 110

In Figure 6, there is shown a modified form of dog or pawl 24^a which is bifurcated at its forward end to receive therein the inner or free end of the arm 21^a, which is coupled in position by means of a pivot pin 37 passed through the bifurcated portions of the dog or pawl and the arm for the purpose. The body of the dog or pawl 24^a is preferably elongated in a rearward direction for the pivot connection 37, and is under-cut, as at 38, at its under side immediately adjacent the pivot 37 and also inwardly of its free end, as at 39 to form therebetween a rearwardly directed pawl tooth 40. The rear end portion of the dog 120 125 130

or pawl body 24^a, above the under-cut 39 is shaped to provide a finger grip 41 by means of which the body is to be lifted from engaged position with the rack teeth 14 for 5 the return of the arms 21^a and the skid members 18 to normally inoperative positions. Offset from the opposite sides of the body 24^a are flange portions 42 which extend beneath the flanges 15 of the bars 12, after the 10 manner of the cylindrical offset portions 21' hereinbefore mentioned. This dog or pawl body 24^a is relatively heavy, so as to be maintained in engagement with the rack teeth 14 under its own weight, combined with 15 that of the arm 21^a, and in its forward movement will ride freely over the forwardly inclined faces of the rack teeth 14, but when the desired limit of forward movement is reached, i. e., the skid members 18 being 20 raised to an inclined position sufficient to assure of the movement of the life boat outboard of the side of the vessel and clear of the side of the vessel and clear of the edge of the deck or supporting surface 10, the 25 tooth 40 will engage the forward face of the nearest of the rack teeth 14 to hold each of the arms 21 in bracing position with respect to the raised skid members. In the use of either of the two forms of dogs or pawls 24 30 and 24^a, to return the skid members 18 and the arms 21 or 21^a to normally inoperative positions, the same will be raised free from their engagement with the rack teeth 14, when they will be moved rearwardly of the 35 channels 13 simultaneously with the gravitation of the skid members 18 and the arms 21 or 21^a to positions of readiness for the next launching operation.

From the foregoing, it will be readily apparent that, while a preferred embodiment 40 of the apparatus has been described and illustrated herein in specific terms and details of construction, arrangement and operation, various changes in and modifications 45 of the same may be resorted to without departing from the spirit of the invention, or the scope of the claims appended hereto.

Having thus fully described the invention, what is claimed, is:—

50 1. In a life boat launching apparatus for vessels, means mounted on the vessel for effecting the hoisting and lowering of a life boat from and to water-borne position, skid members pivoted at their outer ends to and 55 extending inwardly from an edge of the deck of the vessel and normally supporting the life boat in cross-wise relation thereon, means carried by said skid members for securing the life boat in a balanced position thereon,

and means cooperative with said skid members whereby to maintain the same in their raised and outwardly inclined positions. 60

2. In a life boat launching apparatus for vessels, means mounted on the vessel for effecting the hoisting and lowering of a life 65 boat from and to a water-borne position, skid members pivoted at their outer ends at the side edges of a deck of the vessel and extending inwardly therefrom in spaced parallel relation, said skid members being 70 normally supported in parallel relation to the upper surface of the deck and having the life boat resting cross-wise thereon, means carried at the inner ends of said skid members for engaging the inner edge of the 75 life boat to maintain the same in a balanced and secured position, brace arms normally underlying said skid members and pivoted at their forward ends thereto, channeled rack bars set into the surface of the deck beneath 80 said skid members and brace arms, pawls carried at the inner ends of said brace arms and disposed in engagement with said channeled rack bars, and means for releasing said life boat engaging and securing means and 85 thereafter for effecting the tilting of said skid members on their pivots to raised outwardly inclined positions whereby to cause the life boat to slide downwardly thereof 90 to outboard position ready for the lowering operation of said first mentioned means, said skid members, during their raising movements, acting to raise said brace arms to a forwardly inclined position, when the pawls carried by the latter will engage adjacent 95 teeth of said rack bars whereby to maintain the arms and skid members in their raised operative positions.

3. In a life boat launching apparatus for 100 vessels, skid members pivoted at their outer ends to and extending inwardly from an edge of the deck, means for securing a life boat in balanced position thereon, said means forming a handle for raising said skid members into inclined position, and means 105 cooperative with said skid members for maintaining same in raised inclined position.

4. In a life boat launching apparatus for 110 vessels, skid members pivoted at their outer ends to and extending inwardly from an edge of the deck, a boat retaining member pivoted to the free end of each skid member, said retaining member forming an elevating handle for its skid member, and a ratchet bar cooperating with each skid member for 115 retaining same in raised inclined position.

GEORGE WRIGHT.
